Primary Examiner—M. H. Tung(74) *Attorney, Agent, or Firm*—James M. Singer; Pepper Hamilton LLP(57) **CLAIM**

The ornamental design for a transaction card, as shown and described.

DESCRIPTION

FIG. 1 is a front elevation view of a first embodiment of the transaction card, showing my new design;
 FIG. 2 is a bottom plan view of the first embodiment, the top plan view being the mirror image thereof;
 FIG. 3 is a back elevation view of the first embodiment;
 FIG. 4 is a left elevation view of the first embodiment, the right elevation view being the mirror image thereof;
 FIG. 5 is a front elevation view of a second embodiment of the transaction card, showing my new design;
 FIG. 6 is a bottom plan view of the second embodiment, the top plan view being the mirror image thereof;
 FIG. 7 is a back elevation view of the second embodiment; and,
 FIG. 8 is a left elevation view of the second embodiment, the right elevation view being the mirror image thereof.
